UNITED STATES PATENT OFFICE

HARRY D. YOUNG, OF NEW YORK, N. Y., ASSIGNOR TO WOLF BROTHERS & CO., OF RED LION, PENNSYLVANIA, A COPARTNERSHIP COMPOSED OF DAVID E. WOLF AND HARRY C. WOLF

DESIGN FOR A DISPENSING CABINET

Application filed August 20, 1931. Serial No. 40,895. Term of patent 7 years.

To all whom it may concern:

Be it known that I, HARRY D. YOUNG, a citizen of the United States and a resident of the city of New York (borough of Manhattan), in the county of New York and State of New York, have invented the new, original, and ornamental Design for a Dispensing Cabinet, of which the following is a specification.

In the drawing:

The figure is a perspective view of a dispensing cabinet showing my new design.

I claim:

The ornamental design for a dispensing cabinet substantially as shown.

HARRY D. YOUNG.
